Newton S. Leichter, Beverly Hills, and Hugh L. Clary, Pasadena, Calif., assignors to Clary Multiplier Corporation, Los Angeles, Calif., a corporation of California

Application March 13, 1945, Serial No. 118,474

Term of patent 14 years

(Cl. D64—11)

To all whom it may concern:

Be it known that we, Hugh L. Clary and Newton S. Leichter, both citizens of the United States and residents of the city of Pasadena and the city of Beverly Hills, respectively, and both in the county of Los Angeles and State of California, have invented a new, original, and ornamental Design for a Casing for a Calculating Machine or the Like, of which the following is a specification, reference being had to the accompanying drawing, forming part thereof, and wherein:

Figure 1 is a perspective view of a casing for a calculating machine or the like, showing our new design,

Figure 2 is a side elevational view thereof, and Figure 3 is a rear elevational view thereof.

We claim:

The ornamental design for a casing for a calculating machine or the like, substantially as shown.

NEWTON S. LEICHTER.
HUGH L. CLARY.
